Garrett Smith & Henry Brown, of Philadelphia, Pa.

Assignors to

Leibrandt & M. Dowell, of same place.

Letters Patent No 1281, dated July 3, 1860

The schedule referred to in these Letters Patent and making part of the same.

To all whom it may concern:

Be it Known that we, Garrett Smith and Henry Brown, both, of the City of Philadelphia, and State of Pennsylvania, have invented or produced a new & original ornamental design for a cooking stove; and we do hereby declare that the following is a full and exact description of the same, reference being had to the annexed drawings, making a part of this specification in which

Figure 1. is a perspective representation of the stove, and

Figures 2. and 3. transverse sections of the mouldings, respectively, of the top, and bottom, plates thereof, in like letters, when on the different figures, indicating the same objects

The nature of our invention or production consists of certain carved ornamentalations on the plates constituting the sides and front of a cooking stove, and the doors thereof; and also of ... mouldings around the edges of the top and bottom plates, as hereinafter described; which stove, for the purpose of nominal distinction, we call the "Continental".

In the drawings, A, represents the plate, and B & B', the doors of the left side of the said stove - the ornamentalations on the right or opposite side, though not seen in the drawings, correspond with those of the left side in each particular.

C, represents the front plate of the said stove, and D, D', its doors. M, the top plate; and N, the bottom plate.

The side plate A, is ornamented with the figures e & f, and also with a head g, surrounding the word or name "Continental" in raised letters, as seen in figure 1. The ornamentation, e, is, in the right hand of the stove, on a door instead of on the plate A, but, in the same relative position.

The door, B, is ornamented with the figure h, and the door, B', with the figure i, as seen in the drawing.

The front plate (C), is ornamented with the figures h, k, near the side edges of the same; and the doors (D, D) are each ornamented with the figure l, and immediately above the doors, (D, D) the damper (K), projects forward, all as seen in figure 1.

The edges of the top plate (M) are finished with the moulding (p), a transverse section of which is shown by figure 2.

The edges of the bottom plate (N), are finished with the moulding (p), a transverse section of which is shown by figure 3.

All are intended to be cast of metal, and therefore, the ornamentations specified are carved in relief in such a manner, or form, as to be adapted for being readily withdrawn from the sand in moulding, in the usual manner.

What we claim as our own invention or production and desire to secure by Letters Patent is —

1st. The ornamentations e, f, & g, on each of the two side plates (A), the name "Continental" being in letters surrounded by the bead, g, as described.

2nd. We claim the ornamentations (h) on the door (B) and the ornamentation (i), on the door (B'), of both the right and left sides of the stove, as described.

3rd. We claim the ornamentation (l) on each of the front doors (D).

4th. We claim the ornamentations (h, k) on the front plate (C), and also the form of the projecting damper (K) on the same, as shown in the figure;

5th. We claim the moulding (p) around the top plate (M) and

6th. We also claim the moulding (p) around the bottom plate (N), all as and for the purpose herein set forth and Specified.
